SKIMMER

Henry W. McKeen, Hurley, N. Mex.

Application June 11, 1943, Serial No. 490,493

10 Claims. (Cl. 210—51)

In performing known material-separating processes, for example, the flotation process of ore separation, froth or the like must be continuously skimmed from the surface of a liquid, and the present invention aims to provide a new and improved skimmer for this purpose, possessing advantages hereinafter explained.

With the foregoing in view, the invention resides in the novel subject matter hereinafter described and claimed, description being accomplished by reference to the accompanying drawings.

Figure 1 is a front elevation, partly broken away and in section showing the skimmer associated with one of the cells of an ore separating apparatus.

Figure 2 is a vertical transverse sectional view on line 2—2 of Fig. 1.

Figure 3 is a top plan view.

Figure 4 is a fragmentary sectional view similar to a portion of Fig. 2 but showing the skimmer controlling cam track adjusted to a different position.

A construction has been disclosed which is well adapted for carrying out the object of the invention and this construction will be rather specifically described, with the understanding, however, that numerous variations within the realm of mechanical skill, may be effected within the scope of the invention as claimed. The disclosure is, therefore, to be construed as illustrative to a large extent rather than limiting.

A tank or cell 5 has been illustrated containing a liquid 6 from which froth or the like 7 must be continuously skimmed into a launder 8. The side walls 9 and back wall 10 of the cell 5 extend upwardly beyond the liquid level and provide an open front enclosure for the skimming mechanism, said side walls 9 constituting rigid supports for all parts which must be stationarily mounted.

Bearings 11 are shown secured to the side walls 9, said bearings rotatably supporting a horizontal shaft 12, this shaft being provided with two cross arms 13 near the side walls 9. One end of each cross arm 13 extends in the same direction from the shaft 12 as the corresponding end of the other cross arm 13, and the other two ends of said cross arms project in the opposite direction from said shaft, the latter being connected with the cross arms at their centers, whereby said shaft and cross arms constitute a balanced rotatable member to be driven continuously in any preferred manner. For illustrative purposes, a V-type pulley 14 is shown on one end

of said shaft for engagement with motor-driven belts (not shown).

Four skimmer-carrying levers 14 are pivoted to the four ends of the cross arms 13 respectively, the pivots 15 being at one end of said levers 14 in the present showing, said pivots being parallel with the shaft 12 to permit swinging of the levers 14 toward and from said shaft as said levers are carried along continuous paths 10 by the cross arms 13 during operation of the machine. The levers 14 carry a skimmer 16 which, in the present disclosure, is pivotally hung loosely from the outer ends of said levers, the pivots being shown at 17. Each skimmer 16 preferably comprises an upper plate section 18, a lower plate section 19, and a bolt-and-slot or equivalent adjustment 20 connecting said plate sections 18 and 19 for relative vertical adjustments. The plate section 18 is secured to the pivots 17 and it will thus be seen that the plate section 19 may be adjusted vertically with respect to said pivots to vary the depth of skimming.

The four levers 14 are provided with lateral shoes 21 which are shown located between the ends of said levers, said shoes being preferably in the form of rollers. Cooperable with these shoes or rollers are two continuous cam tracks 22 which control the pivotal movements of the levers 14 with respect to the cross arms 13 during operation of the machine and, therefore, control the paths on which the skimmers 16 move. Each cam trackway 22 includes an inclined portion 23 which determines the line upon which the skimmer 16 will move during its forward skimming stroke. Each cam trackway also includes an arched portion 24 which controls the lines on which the skimmers move as they travel upwardly, rearwardly and downwardly during machine operation, the legs 25 of the arched portion 24 being connected with the ends of the inclined portion 23. The two cam trackways 22 surround the shaft 12 and due to this location and to their formation, they will cause such movements of the skimmer-carrying levers 14 that said skimmers will remain retracted except during their skimming strokes and immediately prior to such skimming strokes, it being thus possible to operate the skimming mechanism within limited space.

With the cam trackway 22 positioned about as seen in Fig. 2, each skimmer 16 will move on substantially a horizontal line during its forward or skimming stroke, and it will be seen that this stroke starts well toward the back wall 10 of the

cell 5 and terminates well toward the front wall 10' of said cell, it being thus insured that the froth or the like 7 shall be skimmed from substantially the entire surface of the liquid 6.

In order to permit changing of the lines on which the skimmers 16 travel during their forward skimming stroke, to perform the skimming at one depth toward one end of said stroke and at another depth toward the other end, whenever such skimming should be desirable, I have provided a construction which permits the two cam trackways 22 to be turned to any one of various different positions, one of which is indicated in Fig. 4. In order to accomplish this in a simple manner, the elements 26 and 27 used in constructing the trackway 22 have been shown secured by rivets 28 and 29, to a pair of vertical plates 30 lying against the cell side walls 9 and fastened to these side walls by means of bolts 31 which pass through mere bolt holes in said walls 9 but pass through slots 32 in the plates 30, said slots being concentric with the shaft 12 in the present disclosure. By loosening the bolts 31, the two plates 30 and the elements 26 and 27 carried thereby, may be turned to the desired position and then locked in this position by retightening said bolts. It will thus be seen that the direction taken by the skimmers 16 in performing their skimming strokes, may be varied as required. Attention may also be invited to the fact that this skimming stroke need not in all instances be on a straight line, as an upward and downward movement of the skimmer could be effected by suitably shaping the cam trackway 22.

Above, I refer to elements 26 and 27 used in forming the cam trackway 22. These elements may be of any desired construction. For illustrative purposes, element 26 is simply shown as a plate with its edge suitably shaped to form the inner wall of the trackway 22, and element 27 is simply a distorted ring, for instance, of strap metal, suitably shaped to constitute the other wall of said trackway.

In ore dressing flotation, it is recognized that the mineral to be recovered is suspended on the surface of the bubble and that if the bubbles are broken, the mineral precipitates. It is, therefore, desirable that the froth be skimmed with the least possible disturbance of it. With my invention, the cam track can be shaped to cause the skimmer to enter the froth in a perpendicular position and with substantially no forward motion so that there is a minimum disturbance of the suspended elements contained in the cell. The cam tracks can also cause the skimmer to move in a predetermined positive path and over substantially the entire area of the top of the cell. That is a big improvement over prior skimmers of the type employing a rotary paddle at the discharge edge of the cell and also the type employing endless chains with skimming paddles fixed to the chain links. In the latter type, the lower reaches of the chains sag and it is not possible to operate them so that skimming blades travel in a straight horizontal path and at a uniform depth in the froth. By tests, I have found in the recovery of copper, that with a machine constructed in accordance with my invention, I am able to deliver approximately a five-fold increase in the volume of the concentrate over the rotary paddle type which is the one now largely in use.

It is also generally recognized that the particles of mineral tend to submerge if allowed to remain in the water long enough to absorb water, and hence, there is a definite time interval indicated

between skimming strokes. This is possible only with a full-surface skimmer because the other type depends upon a haphazard flow of the froth before it comes within the range of the skimmer.

5 My skimmer makes it possible to control definitely the time interval between strokes resulting in a higher grade of concentrate. With my invention, I have obtained in addition to the above stated increase in volume, a five percent increase in the desired mineral (copper) content. This is due not only to the full surface skimming movement but also the lack of disturbance to the froth and the straight sageless path followed by the skimmer blades, making it possible to skim at an exact predetermined depth.

It will be noted that in my machine, all of the friction bearing surfaces are clear of the abrasive material in the feed since the tracks, arms and rollers are situated above and toward the ends of the cell away from the path followed by the skimmer blades or paddles as they return above the main shaft, thus preventing any drippings from coming in contact with such bearing surfaces.

25 From the foregoing taken in connection with the accompanying drawings, it will be seen that novel and advantageous provision has been made for carrying out the object of the invention.

The skimmers and their carrying levers 14 remain retracted except when needed, and as the levers 14 of either skimmer 16 more or less complete a final downward movement, said levers are rearwardly projected to position the skimmer 16 close to the back wall 10. The skimmer then

35 travels forwardly on a skimming stroke and at the completion of this stroke, the levers 14 are again retracted and they remain retracted until projection of them is again necessary. The skimming stroke extends substantially over the entire surface of the liquid, whereas most prior devices have skimmed only a small part of the surface at or near the lip of the cell. The horizontal skimming motion or other skimming movement is imparted entirely by a steadily

40 rotating mechanism without the necessity of cranks, cross heads or rotating cams, which is decidedly advantageous in that vibration is practically eliminated and maintenance is kept at the minimum. The skimmers 16 remain suspended by gravity from their carrying levers 14 and do not become seriously inclined even during performance of their skimming strokes, due to the fact that the machine is slowly operated. This slow motion also overcomes or rather

45 prevents injurious results which are often caused in other mechanisms by the action of centrifugal force at high speeds. Not only may the cam guideways be adjusted to change the directions of the lines on which the skimmers move, but as above explained, it is possible to so construct said trackways that an up and down movement of the skimmers could be attained during their skimming strokes, whether such up and down movements are uniform or not uniform.

50 Attention is again invited to the possibility of making variations within the scope of the invention as claimed.

I claim:

55 1. A skimming device comprising a receptacle, a driven member rotatably mounted on a horizontal axis above said receptacle, means for rotating said driven member, a skimmer-carrying lever transverse to and spaced from said axis, a pivot connecting said lever with said

driven member, said pivot being radially spaced from said axis, whereby said driven member will carry said lever upwardly, rearwardly, downwardly, and forwardly on a continuous path, a skimmer carried by said lever and spaced from said pivot to perform a skimming operation at the surface of a liquid in said receptacle as said lever is carried forwardly, a lateral shoe on said lever and spaced from said pivot, and a continuous stationary cam track engaging said shoe to control the pivotal movements of said lever with respect to said driven member as said lever is carried along said continuous path, said cam track having a lower portion for determining the line of travel of said skimmer during its forward skimming stroke, and other portions for determining the line of travel of said skimmer from each skimming stroke to the next.

2. A skimming device comprising a receptacle, a driven member rotatably mounted on a horizontal axis above said receptacle, means for rotating said driven member, a skimmer-carrying lever transverse to and spaced from said axis, a pivot connecting said lever with said driven member, said pivot being radially spaced from said axis, whereby said driven member will carry said lever upwardly, rearwardly, downwardly, and forwardly on a continuous path, a skimmer carried by said lever and spaced from said pivot to perform a skimming operation at the surface of a liquid in said receptacle as said lever is carried forwardly, a lateral shoe on said lever and spaced from said pivot, and a continuous stationary cam track engaging said shoe to control the pivotal movements of said lever with respect to said driven member as said lever is carried along said continuous path, said cam track having an inclined lower portion for determining the line of travel of said skimmer during its skimming stroke, and an arched portion for determining the line of travel of said skimmer from each skimming stroke to the next, the legs of said arched portion being disposed in downwardly converging relation and connected with the ends of said inclined portion.

3. A structure as specified in claim 1; together with means adjustably mounting said cam track for shifting to a different position to change said lines of travel of said skimmer.

4. A structure as specified in claim 1; together with means loosely suspending said skimmer from said lever.

5. A skimming device comprising a receptacle, a horizontal driven shaft rotatably mounted above said receptacle, means for rotating said driven shaft, two spaced arms secured to and projecting radially in the same direction from said shaft, two levers transverse to said shaft, pivots connecting said levers to said arms for swinging movement toward and from said shaft, a skimmer spaced from said shaft and extend-

ing between said levers, pivotal connections between the ends of said skimmer and said levers and loosely suspending said skimmer, said skimmer being located over said receptacle for skimming foam from a liquid in said receptacle, lateral shoes on said levers and spaced from said shaft, and two continuous stationary cam tracks surrounding said shaft and engaging said shoes to determine the pivotal movements of said levers with respect to said arms as the latter carry the levers upwardly, rearwardly, downwardly and forwardly, said cam tracks having portions for determining the line of travel of said skimmer during its forward skimming stroke, and other portions for determining the line of travel of said skimmer from each skimming stroke to the next.

6. A structure as specified in claim 5; together with means adjustably mounting said cam tracks for movement to different positions to change said forward line of travel of said skimmer.

7. A structure as specified in claim 1; said skimmer having a vertically adjustable lower section for varying the depth of skimming.

8. A structure as specified in claim 5; said skimmer being composed of an upper plate section, a lower plate section and means connecting these two plate sections for relative vertical adjustment to vary the depth of skimming, the aforesaid pivotal connections of the skimmer with said arms being connected with said upper plate section.

9. In a skimming mechanism, the combination of a cell, a support associated therewith, a driven member rotatably mounted on a horizontal axis above said cell, means for rotating said driven member, a lever pivoted to said member, a skimmer carried by said lever and located over said cell to perform a skimming movement at the surface of a liquid in said cell, and a cam track and shoe connection between said lever and said support for swinging said lever with respect to said member and causing the skimmer to move in a predetermined path in its skimming movement over said cell when said member is rotated.

10. In a skimming mechanism, the combination of a cell, a skimmer to perform a skimming movement over said cell, a skimmer-actuating means from which said skimmer is pivotally suspended for swinging movement with respect to said skimmer-actuating means, said means including an endless cam track and coacting shoe to travel around said track to cause the skimmer in its skimming movement and means for driving said skimmer-actuating means to move in a substantially perpendicular direction into the froth in said cell and to then move in a predetermined path through the froth to the end of its skimming movement.
